UNITED STATES PATENT OFFICE

2,553,856

CLAMP FOR MASTER SHEETS OF PRINTING MACHINES

Edward J. Janke, Cleveland, Ohio, assignor to Addressograph-Multigraph Corporation, Cleveland, Ohio, a corporation of Delaware

Application March 1, 1946, Serial No. 651,081

3 Claims. (Cl. 101—415.1)

1

The object of this invention is to provide efficient means on the master drum of a printing machine to enable it to hold interchangeably master sheets having different formation at their clamped ends.

In office printing machines operating on the planographic or master-sheet principle it is very desirable to employ master sheets of different characteristics for different uses, for instance, for short runs a comparatively thin paper master having a suitable treated surface may be used; for longer runs a thicker paper master sheet; and for still longer runs a metallic sheet. It has been found most satisfactory to make the thin paper sheets straight across at their ends and imperforate; to make the metallic sheets with scalloped ends, each ear carrying a perforation, while the heavier paper sheets are sometimes made with straight ends and sometimes with a row of perforations behind such straight end.

It is an object of my invention to provide clamping means for the leading and trailing ends of the sheet adapted to hold all of these forms of master sheets.

While the leading end of the sheet may be clamped in fixed position, there is more difficulty with the trailing end clamp, as it should be movable inwardly to apply tension to the sheet, and the present invention is especially concerned with provision on the tensioned trailing end clamp for clamping means to coact with the differently formed master sheets.

My invention is illustrated in the drawings hereof and is hereinafter more fully explained and the essential novel features are set out in the claims.

In the drawings, Fig. 1 is a plan partly broken away of a printing drum equipped with my clamping means, the view showing a master sheet on the drum partly broken away to disclose parts beneath it; Fig. 2 is a plan of an interchangeable pin bar used on the trailing end clamp; Fig. 3 is a sectional end elevation, cross-sectioned through the drum, as indicated by the line 3—3 on Fig. 1; Fig. 4 is a fragmentary view of a portion of the drum and the trailing end clamp open ready to receive a master sheet, this view being taken, for instance, in a plane indicated by the line 4—4 on Fig. 1; Figs. 5, 6 and 7 are cross sections on a larger scale through different portions of the trailing end clamp, as indicated by the correspondingly numbered lines on Fig. 1; Fig. 8 is a sectional view of the parts as shown in Fig. 7 in the act of being separated; Fig. 9 is a plan of a portion of the printing drum with

5 a scalloped perforated master sheet mounted thereon; Fig. 10 is a fragmentary plan of a pin bar forming a portion of the trailing end clamp when set for scalloped and perforated sheet shown in Fig. 9.

In Figs. 1, 3, 4 and 9, 10 indicates a suitable drum adapted to be embraced by a master sheet for the most of the circumference but having an arcuate gap in which is mounted clamps for the 10 leading end and trailing end of the sheet. In Figs. 1 and 3, I have shown a normally imperforate thin master sheet A on the drum and in Fig. 9 a perforated scalloped-end sheet B on the drum.

15 Referring first to the leading end clamp, shown in Figs. 1 and 3, this comprises a longitudinal bar 20, pivotally carried and adapted to coact with an anvil in the form of a flanged bar 22 mounted on the end 11 of the drum shell at the gap. I 20 provide a special form of continuous hinge 24, which has one leaf extending between the anvil and the end of the drum shell. Screws 25 passing through the anvil and this leaf and threaded in the drum shell hold these parts rigidly in position. The free leaf 26 of the hinge is secured by 25 screws or otherwise to the back of the bar 20.

To enable springs to act on the bar 20, tending to seat it, I bend inwardly end portions 27 of the leaf 26 of the spring, as shown in Figs. 1 and 3, and I attach to these inwardly projecting arms 30 tension springs 10, the other ends of which are suitably anchored.

The outer flange 21 of the anvil 22 is preferably continuous to provide a straight edge over which the master sheet may make an abrupt U-turn, as shown in Fig. 2. The flange 23 at the inner end of the anvil is for the purpose of providing a stop to engage the end of the master sheet and enable it to be accurately positioned, very quickly, upon insertion. If desired, this flange may be discontinuous; that is, in the form of two or more tongues registering with receiving notches in the bar 20.

45 The outer surface of the clamping bar 20 is cut off at an angle, as shown in Fig. 3, and mounted on this surface is a bar 28 provided with outwardly and backwardly projecting spaced hooks 29. The inner face of the bar 20, in coaction with the anvil is adapted to kink the end of a thin or imperforate master sheet extending across the flange 21 and effectively hold it, as shown in Fig. 3, whereas the hooks 29 are adapted to enter openings in a master sheet and thus anchor the leading end thereof as shown in Fig. 9, where the master sheet B has scalloped ears b

at each end, each provided with a slot b' through which the hooks 29 may readily extend.

The trailing end clamp, which is adjustable to coact with either an imperforate or perforate master sheet, will now be described.

The shell of the drum 10 is formed at its end opposite the leading end clamp with a flat inwardly extending surface 12 to which I secure, by screws or otherwise, a bent plate, the inwardly projecting free portion of which is slotted to provide a series of teeth 30 , which form the anvil for the movable clamping member, while the attached part 31 may be continuous and secured by screws to the drum shell.

The clamping member to coact with the anvil 30 comprises a longitudinal bar 40 , the ends of which are bent downwardly to provide two arms 42 , each of which is longitudinally slotted at 43 . Extending through the slots are pins 44 pivotally attaching the bar to the drum. Tension springs acting on the bar tend to pull the clamping member inwardly and downwardly toward the anvil 30 . For convenience, I prefer to utilize as these springs the same springs 70 which operate to seat the leading end clamp, each clamp thus forming the spring anchorage for the other clamp.

The member on the trailing end clamp which engages the master sheet comprises a pin bar extending along and secured to the bar 40 . I provide a plurality of these pin bars interchangeably mounted on the bar 40 and carrying differently spaced pins; thus as shown in Figs. 1 to 8, I have provided a pin bar 50 carrying a row of relatively close pins 51 .

The pin bar is removably mounted on the under side of the bar 40 of the trailing end clamp. To effect such mounting I provide the bar 40 with downwardly projecting headed pins 45 (Figs. 7 and 8) and I provide notches 55 in the removable bar 50 adapted to snugly embrace such pins. Likewise, I provide upwardly extending headed pins 56 on the bar 50 and I form the bar 40 with notches 46 adapted to receive such pins. The bar has notches 51 to clear the anchorages of the springs 70 .

Fig. 8 shows the position of the supporting bar 40 and the removable pin bar 50 as the latter is about to be put in place by a movement toward the right, and thus come into the position shown in Fig. 7, where the pin bar is definitely supported by the supporting bar.

To lock the pin bar in its mounted position, I provide a pair of leaf springs 60 anchored adjacent one end to the supporting bar 40 as by rivets 61 , Figs. 1, 6 and 9. Each spring 60 adjacent its free end carries a downwardly extending pin 62 , which may be riveted to the spring, and which extends through an opening in the supporting bar and beyond it so that it is adapted to come into an opening 53 in the pin bar 50 . This prevents the bar shifting in or out, so that it is definitely locked to the supporting bar. The free end of the spring 60 is preferably bent upward slightly as at 64 , Fig. 6, so that it may be readily lifted by one's finger nail.

When the bar 50 is mounted on the supporting bar 40 a clamp such as shown in Fig. 4 results, having the downwardly projecting pins 51 adapted to pass through the master sheet into the spaces between the teeth 30 on the anvil. The prongs 51 are sharpened as shown in Figs. 4 and 5; accordingly, in the case of an imperforate sheet they may act to perforate the sheet and thus form an effective attachment thereto, or

if the sheet is already provided with correspondingly spaced perforations the pins may readily occupy such perforations.

The supporting bar 40 is preferably curled inwardly along its intermediate portion, as shown at 48 , in Figs. 1 and 5. This inwardly projecting edge making a convenient gripping ledge whereby the operator by inserting his fingers beneath the ledge may readily pull the clamp upwardly and outwardly against the action of the tension springs 70 into the position shown in Fig. 4. Then if such clamp is swung downwardly toward the anvil 31 , the prongs or pins 51 pass through the perforated sheet into the transverse spaces between the teeth 30 . Accordingly, the master sheet is effectively clamped between the pin bar and the anvil, while the springs 70 are effective to apply an inward pull to the clamp and thus maintain the master sheet under tension.

If the master sheet is imperforate and adapted to be perforated by the prongs 51 , or if it has a row of perforations spaced according to the pins 51 , then the clamp as stated, may be used with such sheet. However, sometimes the master sheet has a row of perforations spaced differently from the pins 51 on the pin bar 50 and accordingly in that case I replace the pin bar 50 by a corresponding bar $50a$, Fig. 10, and a row of pins 52 differently placed from the pins 51 . This bar is equipped with headed pins $56a$ and edge notches $55a$ and $51a$ and holes $58a$ in the same manner as the pin bar 50 and thus may be readily mounted in place of that bar.

When it is desired to change the trailing end clamp from the condition first described, where it carries the pin bar 50 , it is only necessary for the operator to lift the two springs 60 to free the pins 62 from the pin bar and slide out the pin bar and slide in another pin bar, such as the bar $50a$ of Fig. 10, the returning pin 62 on the springs then holding that bar rigid with the supporting bar 40 .

The pins on the bar $50a$ are shown in Figs. 10 as positioned with reference to the openings b' on the scalloped and perforated master sheet B of Fig. 9. The pins 52 therefore are spaced in accordance with the spacing of the hooks 29 on the leading end clamp.

I have arranged the comb comprising the teeth 30 of the anvil so that the spaces between these teeth will be available for pins 51 , spaced as shown in Fig. 2, or pins 52 , spaced as shown in Fig. 10. In effecting this spacing, I position the teeth nearly equally spaced but in certain regions omit a tongue altogether as shown in Fig. 1. Notwithstanding the omission, the toothed comb of Fig. 1 cooperates effectively with the continuous closely spaced pins of Fig. 2, most of these pins entering a single narrow opening between adjacent tongues but occasionally two pins entering a single wider opening. Now when the pin bar of Fig. 10 is used the pins 52 thereof will come in alternate spaces between the teeth of the comb. Hence the same comb is available for both pin bars.

It will be seen that by the simple arrangement of interchangeable pin bars with an anvil comb common thereto, and the provision of a leading end clamp adapted to hold both imperforate and perforated sheets, I am enabled to take care on a single drum of master sheets having widely different end formations, namely, imperforate ends, straightened perforated ends, and scalloped perforated ends, and the drum thus

equipped can accordingly take care of these differently formed sheets, such as are now on the market.

I claim:

1. The combination of a drum having a gap, a pivotally mounted supporting bar therein, a pin bar having a row of projecting pins, headed pins on one of said bars and notches to receive them on the other bar, whereby the pin bar may be mounted on the supporting bar by sliding action, an anvil on the drum, and spring means acting on the supporting bar to press the pin bar toward the anvil.

2. The combination of a drum having a gap, a movable supporting bar within the gap extending lengthwise of the drum, a removable pin bar, upwardly projecting headed pins on the pin bar, notches on the supporting bar registering therewith, downwardly projecting pins on the supporting bar and notches on the pin bar registering therewith, whereby the pin bar may be slidably mounted on the underside of the supporting bar, and an anvil on the drum having openings to receive the pins.

10

5 3. The combination of a drum having a gap, a pivotally and slidably mounted supporting bar therein, a removable pin bar, devices on the supporting bar and pin bar for holding them together slidably, a pair of leaf springs on the supporting bar, pins carried thereby adapted to occupy openings in the pin bar to lock it in place on the supporting bar.

EDWARD J. JANKE.
